UNITED STATES PATENT OFFICE.

WILLIAM F. LAUTENSCHLAGER, OF CINCINNATI, OHIO.

CEMENT-APPLYING MACHINE.

1,225,828.

Specification of Letters Patent.

Patented May 15, 1917.

Application filed June 5, 1916. Serial No. 101,840.

To all whom it may concern:

Be it known that I, WILLIAM F. LAUTENSCHLAGER, a citizen of the United States, residing at Cincinnati, in the county of 5 Hamilton and State of Ohio, have invented certain new and useful Improvements in Cement-Applying Machines, of which the following is a specification.

My invention relates primarily to cement-10 string controlling means, and means for wiping the laid cement, and is an improvement upon the cement applying machines shown, described and claimed in my applications for Letters Patent of the United 15 States, Serial No. 39,802, filed July 14th, 1915, and Serial No. 46,268, filed August 19th, 1915.

Cement applying machines to which my improvement relates are applicable for providing the margins of flexible material, such as leather, cloth and fabrics of various kinds with a narrow band of cement in the manufacture of shoe-uppers, gloves, pocket-books and containers of various kinds. 25 These margins are skived at times, especially when the flexible material operated upon is in the nature of shoe-uppers.

The cement employed in this art usually contains rubber, and is "tacky" or gummy 30 at the time of its application, and has a tendency to form strings which may at times take the form of a film of cement between the point of cement application to the margin and the cement-applier. The 35 cement also has a tendency to form drops or small balls which are liable to drop upon the material, which is detrimental.

I have also found that when employing a 40 rotary cement-applier in cementing convexly curved margins that the cement strings have a tendency to pull the cement away from the extreme outer edge of the margin and thereby leave the said extreme outer edge uncemented.

45 In order to overcome the objections stated, I have provided a yieldable cement-control acting to wipe the cement-strings or film lengthwise of the margin and to direct surplus cement back toward the cement- 50 applier.

It is the object of my invention further

to provide a yielding cement-control at the feeding-out side of the cement-applier, acting preferably to resiliently wipe the applied cement, and further to provide a 55 brush at the feeding-out side of the rotary cement-applier with relation to which the cement-applier has rotation, and the invention will be further readily understood from the following description and claims, and 60 from the drawings, in which latter:

Figure 1 is an end elevation of so much of a cement-applying machine as is necessary to illustrate my invention.

Fig. 2 is a front elevation of the same. 65

Fig. 3 is a rear elevation of the same.

Fig. 4 is a vertical axial section of the same taken on the line 4—4 of Fig. 1.

Fig. 5 is a bottom view detail of the same.

Fig. 6 is a vertical cross-section taken on 70 the line 6—6 of Fig. 2.

Fig. 7 is a vertical cross-section taken on the line 7—7 of Fig. 2.

Fig. 8 is a perspective view of the cement-applying means, showing the cement being 75 applied to the margin and viewed from the feeding-out side and away from the operator.

Fig. 9 is a perspective view of the same, viewed toward the operator and from the 80 feeding-in side; and,

Fig. 10 is a side elevation, showing the cement application upon the margin of a piece of material, the material being cut away proximate to the plane of the feeding- 85 out side of the cement-applier.

The cement applying instrumentalities may be mounted upon a suitable frame, for instance as shown in my aforesaid application, Serial No. 39,802, and the cement- 90 applier rotated and the feeding of cement caused in manner as therein shown and described.

Instancing this arrangement, 21 represents the main frame, which may have a 95 laterally and forwardly projecting arm 22 extending therefrom. A cement-pot 23 is fixed in a bearing 24 of the arm. A cement-passage 25 extends therefrom to a cement-valve 26 for controlling the flow of cement. 100 29 is a cement-supplying roller at the lower end of the cement-passage 30 in the valve.

- The cement-supplying roller is provided with cement-supplying recesses 31, arranged to receive the cement and feed the same to a cement-applier 32, exemplified as a rotating brush. 73 between the shaft and hub of the brush 65 in line with the sleeve.
- The cement-supplying roller is instanced as rotating in the direction of the arrow *a*. The cement-applying brush is instanced as rotating in the direction of the arrow *b*. The material-supporting face of the support or horn is arranged to be adjusted up or down according to the thickness of the leather or material being cemented. The 70 material 74 being cemented may be skived as shown at 75. The material-supporting face of the support or horn approaches the axis of the rotating brush at its rear, thereby insuring that intimate contact between 75 the outer edge of the margin being cemented and the rotary brush is maintained.
- Means for rotating these devices may be instanced as a shaft 35, rotated in suitable manner, as by means of a pulley 36, and having thereon a gear 37. The gear 37 meshes with a gear 38, fast on a shaft 39, 10 journaled in a bearing 40 in the forward extension 41 of the arm 22. The gear 38 meshes with a gear 42 on a shaft 43, journaled in a bearing 44 of said forward extension. The cement-applier 32 is mounted 15 about the shaft 43 in manner hereinafter explained.
- The shaft 39 has a gear 46 fixed thereon, which meshes with a gear 47 fast on a shaft 48, journaled in bearings 49, and having the 20 cement-supplying roller 29 fixed thereon.
- The margin of the flexible material is arranged to move crosswise of the cement-applying brush, instanced in the present exemplification as accomplished by manual 25 means, being moved past the cement-applying brush crosswise thereof by the hands of the operator, and guided on a forwardly extending support 51, located at the feeding-in side of the rotary cement-applying brush, 30 and by a gage 52 adjusted upon said support for increasing or decreasing the width of the margin presented to the cement-applying brush during cement application. It is movable, for instance, forward and back 35 on the support 51 and fixed in place by a clamp-screw 53, which passes through a slot 54 in the support and has threaded connection 55 with the gage. The gage has an upper flaring finger 56 thereon. The margin 40 of the material is arranged to be received in the recess 57 between the finger and support for guiding the same, this recess having a gradually widening mouth for readily receiving the edge of the margin.
- The support may also be raised or lowered 45 and held in adjusted positions by means of clamp-screws 58 received through a slot 59 in the shank 60 of the support, and threaded in threaded apertures in the arm 22.
- The brush is provided with annular rows 55 of bristles, separated by rings 66 about a bushing 67. The bushing is arranged to be 60 adjustably secured to a sleeve 68 by means of a set-screw 69. The sleeve is rotatively fixed to the shaft 43 by means of a pin 71 in the shaft received in an end slot 72 in the inner end of the sleeve. The outer end of the sleeve is spaced from the outer end of the shaft 43 for forming an annular recess
- In operating the machine, in the present exemplification, the operator is seated in front of the cement-applying head, as 80 viewed in Fig. 2, that is, facing the front of the machine, which front is marked *f* in Fig. 1. The normal direction of feeding the material is indicated by the arrow *c* in Figs. 8 and 9, the side *d* of the rotary cement-applier being therefore the normal feeding-in side, and the side *e* of said part being the 85 normal feeding-out side thereof.
- The gage with its support is located at the feeding-in side of the rotary cement-applying brush and its edge proximate thereto is 90 preferably spaced from the bristles of the brush by a slight space 76, for permitting the material to be flexed about the periphery of the brush at its point of cement application, as indicated at 77, without undue flexure of the bristles of the brush and for insuring intimate contact between the margin being cemented and the periphery of the 95 brush.
- This space also permits the ready passage 100 of cross-seams, when such are contained in the margin, as when cementing closed vamps.
- The degree of pressure of the margin of the material upon the periphery of the brush is readily regulated by the force applied by the hands in stretching the material between the hands at the point of cement application, and also by the direction above or below the 110 plane of the cement-applying portion of the brush in which the feeding-out portion of the margin is held.
- The feeding movement of the material 115 may be accomplished by manual manipulation or by mechanical feeding means.
- The movement of the cement-applier crosswise of the margin causes a "stringing", as shown at 78, of the cement at the feeding-out side of the brush, this stringing sometimes taking the form of a thin film of cement. 120
- The stringing is especially noticeable when the cement-applier is a rotary cement-applying brush, which I have found best for cement application, as the pressure of the margin upon the bristles and the feeding of the margin lengthwise of the margin and

crosswise of the rotating brush, causes lateral flexure of the bristles of the brush at the point of cement application, and a tendency of the cement to follow the feeding movement of the margin resulting in the stringing mentioned.

In order to control the said stringing of the cement and preferably also to aid in the laying of the cement, I provide a yieldable cement control 80 at the feeding-out side of the cement-applier.

This cement control is shown as a brush, with relation to which the cement-applying brush has rotation. It is shown mounted on a plate 81 received about the axis of rotation of the cement-applying brush, being provided with an annular flange 82 at its middle portion which is received about the shaft 43 in the annular recess 73. The plate 20 adjacent to the flange contacts the hub of the cement-applying brush, as shown at 83, for preventing seeping of cement to the brush-shaft. It is held on the shaft by means of a screw 84 which has threaded 25 connection with the end of the brush-shaft.

In order to prevent rotation of the plate with the shaft and cement-applying brush, it is provided with a tail-piece 85, arranged to contact the cement-applying head, for 30 limiting its rotative movement about the shaft in one direction, but permitting an oscillation of the plate about the shaft, if such should be desired, for cleaning purposes.

The plate is provided with a laterally sloping wall 88 at the side of the initial part of the cement-feeding portion of the rotary brush, adjacent to the cement-supplying roller, forming a clearance space 89 for 40 the cement at the feeding-out side of the rotary brush which tapers toward the brush. This clearance space permits ready wiping of the cement off the cement-supplying roller by the rotary brush.

This laterally sloping wall merges into a radially extending wall 90, which extends substantially to or beyond the peripheral line of the rotary brush, in close proximity to the bristles of the rotary brush, and, in 50 connection with said first-named wall, directs the cement at the feeding-out side of the rotary brush toward the ends of its bristles.

The peripheral edge of the plate at that portion thereof proximate to the normal cement-applying portion of the rotary brush, and in advance of the material-supporting surface of the material-support, is located inwardly from the longitudinal projection 60 of the periphery of the rotary cement-applying brush, as shown at 91, so that the bristles of the rotary brush may project beyond said edge.

The character of the cement employed,

which is a tacky, gummy and adhesive substance, and the relative movement between the margin being cemented and the rotary cement applier, have a tendency to cause stringing of the cement between the outer edge of the margin and the periphery of the cement-applier, as seen by the strings 78. It is understood that the bristles of the rotary brush are flexed during cement application and move past said outer edge in contact therewith. These strings of cement 75 normally extend from said margin to the periphery of the rotary brush and would normally follow the periphery of the rotary brush in its rotation and cause the end of the rotary brush and the plate to be in time 80 covered with cement, which would eventually drop in drops or lumps on the material, and be uncleanly.

In order to prevent this undesirable condition, I have provided the yieldable cement control, which preferably extends rearwardly of the margin and beyond the periphery of the rotary cement-applier crosswise of the margin being cemented. (See Fig. 10).

The yielding cement control is preferably in the form of a narrow brush extending crosswise of the margin, the bristles of which are resilient and act to arrest the cement strings and lay the same toward the margin being cemented, so that the extreme outer edge of the margin may have cement applied thereto, and act also to brush the cement lengthwise of the margin. The 100 bristles of the cement-control brush preferably act to brush across the oblique ridges 93 of cement formed by the rotary cement applying brush upon the margin fed crosswise thereof, to crossline the same as indicated at 94 in Fig. 8. The yielding cement control further tends to arrest the surplus cement and the rotary cement-applier takes the surplus cement with it in its rotation to the cement-supplying roller, and thereby 105 prevents the dropping of drops, beads or tears of cement on to the material being cemented.

The resilient bristles of the cement-control brush have a continual tendency to move toward the rotary cement-applier, and act resiliently upon the margin. The operator is thereby aided in controlling the thickness of the cement-application, as the manual raising of the outgoing stretch of the material being cemented increases the pressure upon said control for decreasing the ready passage of the applied cement, although the resilience and separation of the bristles of the cement-control brush avoid the wiping of the applied cement from the margin. The movement of the outgoing stretch of the material away from the line of the axis of rotation of the ro-

tary cement-applier will permit the more ready passage of the applied cement on the margin past said control.

The yielding or resilient feature of the 5 cement control has the further advantage that thereby seams are allowed to readily pass the control, and, if desired, to permit seams to be moved past the cement control in reverse direction for allowing the seams 10 to be passed back and forth across the rotary cement-applier, for instance, when it is desired to apply cement under the flaps of the seams.

Having thus fully described my invention 15 what I claim as new and desire to secure by Letters Patent, is:

1. In a machine for applying cement to the margin of flexible material, the combination of a rotary cement-applier, a margin 20 supporting and guiding means at the feeding-in side of said rotary cement-applier for guiding said margin in a path crosswise of the path of rotation of said rotary cement-applier, and a yieldable cement-control at the feeding-out side of said rotary cement-applier extending crosswise 25 of the position of the margin guided by said margin supporting and guiding means.

2. In a machine for applying cement to 30 the margin of flexible material, the combination of a rotary cement-applier, a margin supporting and guiding means at the feeding-in side of said rotary cement-applier, and a resilient cement-control at the 35 feeding-out side of said rotary cement-applier, the margin supporting surface of said margin supporting and guiding means and the cement-contacting face of said resilient cement-control extending in crossing planes.

3. In a machine for applying cement to 40 the margin of flexible material, the combination of a rotary cement-applying brush, margin supporting and guiding means at the feeding-in side of said rotary brush, and a yieldable cement-control at the feeding-out 45 side of said rotary brush extending across the cylindrical projection of the periphery of said rotary cement-applying brush.

4. In a machine for applying cement to 50 the margin of flexible material, the combination of a rotary cement-applying brush, margin supporting and guiding means for guiding said margin in a path crosswise of the path of rotation of said brush, and a yieldable cement-control brush at the feeding-out side of said rotary cement-applying brush with relation to which said rotary cement-applying brush rotates, said yieldable cement-control brush forming a yieldable cement-string arrester.

5. In a machine for applying cement to the margin of flexible material, the combination of a rotary cement-applier and a gage for the margin of flexible material, arranged for

feeding movement of the margin crosswise 65 of said rotary cement-applier and lengthwise of the margin, and a laterally yieldable cement-string control at the feeding-out side of said rotary cement-applier.

6. In a machine for applying cement to 70 the margin of flexible material, the combination of a rotary cement-applier and a gage for the outer edge of the margin of the flexible material, arranged for feeding movement of the margin crosswise of said rotary cement-applier and lengthwise of the margin, and a yieldable cement-string control 75 at the feeding-out side of the said rotary cement applier extending across the outer edge of said margin.

7. In a machine for applying cement to the margin of flexible material, the combination of a rotary cement-applier and a gage for the outer edge of the margin of the flexible material arranged for feeding movement of the margin crosswise of said rotary cement-applier and lengthwise of the margin, said rotary cement-applier provided with a flexing periphery having flexing movement across the outer edge of said margin, and a yielding cement-string control at the feeding-out side of said rotary cement-applier extending across said periphery and said outer edge.

8. In a machine for applying cement to 95 the margin of flexible material, the combination of a rotary cement-applier and a gage for the margin of the flexible material arranged for feeding movement of the margin crosswise of said rotary cement-applier and lengthwise of the margin, and a cement-laying brush extending crosswise of said margin at the feeding-out side of said rotary cement-applier with relation to which brush said rotary cement-applier has rotation.

9. In a machine for applying cement to the margin of flexible material, the combination of a rotary cement-applying brush having a cement-applying periphery, and a cement-laying brush proximate to the cement-applying portion of said periphery at the feeding-out side of said rotary cement-applying brush and extending within and outside the cylindrical projection of said periphery.

10. In a machine for applying cement to the margin of flexible material, the combination of a gage for the outer edge of said margin, a rotary cement-applying brush rotating in a path crosswise of said margin, and a cement-laying brush extending across the position of said margin when guided by said gage, and constructed and arranged whereby to feed said margin lengthwise of said margin across said gage and rotary cement-applying brush and whereby the angle of presentation of said outer edge of said margin to said cement-laying brush is

manually controlled for controlling the flexure of the bristles of said last-named brush.

11. In a machine for applying cement to the margin of flexible material, the combination of a gage for the outer edge of said margin, a rotary cement-applying brush comprising annular rows of separated bristles rotating in a path crosswise of said margin constructed and arranged whereby to feed said margin lengthwise of said margin across said gage and rotary cement-applying brush for applying the cement in

oblique ridges to said margin, and a cement-laying brush extending crosswise of the position of said margin and the bristles 15 whereof act to crossline said ridges.

In testimony whereof, I have hereunto signed my name in the presence of two subscribing witnesses.

WILLIAM F. LAUTENSCHLAGER.
